(57) **CLAIM**

The ornamental design for a charger device, as shown and described.

DESCRIPTION

FIG. 1 is a front, top, right perspective view of the charger device showing our new design;

FIG. 2 is a left view thereof;

FIG. 3 is a right view thereof;

FIG. 4 is a top view thereof;

FIG. 5 is a bottom view thereof;

FIG. 6 is a front thereof; and,

FIG. 7 is a rear thereof.

The broken lines shown in FIGS. 1-7 are included for the purpose of illustrating environmental elements only and form no part of the claimed design.
